UNITED STATES PATENT OFFICE

RALPH H. LEFFLER, OF BATAVIA, ILLINOIS

ELECTROSTATIC REPRODUCER

Application filed January 18, 1929. Serial No. 333,492.

The present invention relates to an electrostatic reproducer for the reproduction of phonograph records and the like and has to do with an improved mechanism for the electrical reproduction of such records.

One object of the present invention is to provide a reproducer of the electrical condenser type in which there are no coils of copper or other wire, iron cores, or permanent 10 magnets. Thus eddy current losses, hysteresis losses, and the effect of saturation, all of which are inherent to electrical reproducers of the magnetic type, are eliminated and improved reproduction obtained.

Another object of the present invention is to provide a reproducer of the electrostatic type in which the vibrations of one plate react electrically upon fixed plates on opposite sides of said vibratory plate, such reproducer 20 operating in conjunction with a special vacuum tube circuit in which advantage is taken of the inverse capacitance variation thus obtained to produce a cumulative effect in the output of the said vacuum tube circuit. Substantially double the effect may be obtained 25 from unit motion of the vibratory member in such an arrangement over that which may be obtained when a single stationary plate functions in conjunction with a vibratory 30 plate.

Another object of the present invention is to provide a symmetrical mechanical arrangement for the vibratory and stationary plates of such a reproducer.

Another object of the present invention is to provide equal damping effects upon opposite sides of a vibratory plate longitudinal to the direction of motion.

An additional object is to provide means 40 for mounting a vibratory plate in conjunction with a stylus whereby to cause in such vibratory plate a large volume of motion relative to unit motion of the stylus.

Another object of the present invention is to provide means for insulating acoustically 45 from the stationary parts of a reproducer the vibratory parts thereof.

A further object of the present invention is to provide in an electrostatic reproducer 50 means for adjusting the spacing of stationary

plates longitudinally to the vibratory plates.

Another object of the present invention is to provide means for adjusting the spacing of stationary plates in a condenser reproducer transversely relative to the length of 55 a vibratory plate therein.

Another object of the present invention is to provide means for adjusting the thickness of an air gap dielectric between the faces of 60 stationary plates and the co-operating vibratory plate in a condenser reproducer.

Another object of the present invention is to provide a mechanical structure for a vibratory plate, fulcrum, stylus, and adjusting element in a reproducer such that the total 65 mass, and consequently the mechanical inertia thereof, is reduced to a minimum.

The principal object of the present invention is to provide an electrical reproducer having qualities of reproduction superior to 70 that obtainable from reproducers of the magnetic type, and to that of heretofore designed reproducers of the condenser type.

These, and such other objects as may hereinafter appear, are obtained from the novel 75 combination, unique construction and improved arrangement of the elements incorporated into the one form of the present invention disclosed in the accompanying single sheet of drawing hereby made a part of this 80 specification.

In said drawing:

Figure 1 is a schematic representation, in cross-section, of the spaced positions of two 85 fixed condenser plates relative to vibratory parts including a plate, a fulcrum, and a stylus;

Figure 2 is a schematic side elevation illustrating the relative proportions of the vibratory parts comprising a plate, a fulcrum, a 90 set screw, and a stylus;

Figure 3 is an end elevation of the vibratory plate shown in Figure 2 and in conjunction with Figure 2 illustrates the means employed to reduce the mass of the vibratory parts, and consequently the mechanical inertia thereof, to a minimum.

Figure 4 is a cross-section through a condenser-reproducer illustrating means employed to adjust the thickness of the air gap 100

dielectric between stationary plates and a vibratory plate associated therewith, also means to adjust said stationary plates longitudinally to the length of the vibratory plate;

5 Figure 5 is a transverse cross-section in the line 5—5 of Figure 4, looking in the direction of the arrows.

10 Figure 6 is a vertical section illustrating in detail means employed to insulate acoustically the fulcrum of vibratory parts from the main body of a reproducer by the use of damping materials and also shows means employed to vary the tension upon the fulcrum by an adjusting member in conjunction with its locking device;

15 Figure 7 is a front elevation schematically illustrating in detail one means employed to obtain equal damping effects on opposite sides of a vibratory plate longitudinal to the direction of motion.

20 Figure 8 is a side elevation illustrating the means upon the stationary plates to adjust the spacing between said stationary plate and 25 the vibratory plate transversely of the vibratory plate; and

25 Figure 9 is a schematic representation of a circuit in which such a reproducer may be employed.

30 That portion of the reproducer which is associated with the grid circuit shifts the frequency of the oscillator with variations in the capacitance, while that portion associated with the anode circuit causes a shift in the 35 resonant point of the modulating circuit, the combined effects being so phased that the resultant currents are cumulative in so far as the currents flowing in the anode circuit are concerned.

40 Like reference characters are used to indicate similar parts in the drawing and in the hereinafter given description of the apparatus.

45 In the present invention there is an improved electrostatic reproducer having no coils, permanent magnets, or magnetic circuits of any kind. As is shown schematically in Figure 1, the fundamental elements of such condenser reproducer comprise fixed 50 metallic plates, 1 and 2, and a movable or flexible metallic plate 3. These plates form an electrostatic condenser, the air gap between the several plates being the dielectric.

55 As is well known, the capacitance of an electrical condenser is an inverse function of the depth or thickness of the dielectric between the conducting plates which it separates. This being true, it is to be observed that as plate 3 is made to move towards the right (of Figure 1) by a stylus 5 acting upon a fulcrum 4, as when the stylus 5 is following the groove 39 of a phonograph record, the capacitance between 1 and 3 is made to increase while the capacitance between 2 and 65 3 is made to decrease at exactly the same rate

because the movable plate 3 is located between the two fixed plates 1 and 2. This statement assumes for predication, of course, that the movable plate 3 is located midway between and its faces are parallel to plates 1 and 2, 70 resulting normally in equal air gap dielectrics at each side of plate 3.

75 When the motion of plate 3 is towards the left, the effect is exactly the opposite to that above described, that is, the capacitance between plates 2 and 3 increases while that between plates 1 and 3 decreases. Thus, as the stylus 5 passes along the groove 39 of a phonograph record, capacitance variations occur in the reproducer at nearly the same 80 rate as the rate of change of curvature of the groove 39 of the phonograph record.

85 The amount of deviation from a linear capacitance to motion rate of change is governed, among other factors, by the amount 90 of the non-parallelism between the stationary and the movable plates. These capacitance variations may be made to cause a similar rate of change in an electric current in a suitably designed amplifier circuit, and thus 95 a high quality of reproduction is obtained.

100 It is to be further observed that the two fixed metallic plates 1 and 2 are not in metallic connection with one another, but are kept electrically separate, thus forming with plate 3, in reality, two small variable condensers, one comprising the plates 1 and 3, and the other the plates 2 and 3. These two variable condensers may be connected in a vacuum tube circuit in such a way that their inverse 105 capacitance variations produce a cumulative effect in the output circuit. (See applicant's heretofore filed application for Letters Patent, Serial Number 309,551, filed October 1, 1928, entitled Amplifying system, and Figure 9 of the drawing in this application.)

110 Reference should now be had to the vibratory parts shown in Figures 2 and 3. By the structure shown, a relatively large amount of mechanical motion of a movable plate 3 relative to the motion of a stylus 5 is obtained. The pivot or fulcrum of motion is at 4, close to the point 36 of the stylus 5, the fulcrum 4 is small in comparison with the distance 115 from the fulcrum 4 to the other end of plate 3.

120 Thus, a lever multiplying action is obtained and therefore a small amount of motion at the stylus point 36 produces a much greater movement of plate 3, and consequently results in large capacitance variations in 125 the condensers formed by plates 1 and 3, and plates 2 and 3, and this results in a large current variation and volume of sound output in a suitable circuit in which the device is employed, as for example, that shown in Figure 9.

130 For the purpose of supporting the two condensers or double condenser of the herein described apparatus, there is provided suitable frame or housing therefor. One form

only is illustrated in Figure 5, which comprises a cross-section through such a frame or housing and illustrates and discloses in conjunction with Figures 5, 6, 7 and 8, the relationship existing between the various condenser parts and the stylus.

Any suitable configuration may be adopted for the housing of the condenser. Likewise any satisfactory combination of parts 10 may be employed for forming such housing.

The shape or style of the housing is immaterial. Any device which holds the required parts, only one form of which is here shown, will suffice.

15 In that form of housing illustrated in Figure 4 there are side pieces, 40 and 41, and a top member 42 and a bottom member 43. Intermediate the side members 40 and 41 and the top and bottom members, 42 and 43, there 20 are connecting means, illustrated in the accompanying drawing as screws. In the bottom member 43, there is an aperture 44 through which access is had to the inside of the housing or frame and it is through this 25 aperture that the movable condenser plate 3 and its associated parts is inserted.

The mounting for such movable condenser plate is secured at the bottom of said housing, and the mounting therefor, best illustrated 30 in Figure 6 is adapted to be attached thereto by a plurality of screws or other suitable fastening members 44' and 45'.

Within the housing, the fixed plates 2 and 3 are disposed, each being situated substantially equidistantly from the side members 40 and 41. To obtain an adjustment toward and away from the movable condenser element, each fixed condenser plate is mounted upon a carrier block 46. Such carrier 40 block has two threaded apertures 47 in the top thereof, and another 48 in the bottom thereof.

From the sides 40 and 41 of the device 45 to and into each aperture, a machine screw 49 is disposed. Blocks of insulatory material, such as for example, blocks 10 and 11 may be attached to the side members 40 and 41. About the shank of such screw and intermediate the internal surface of the side 50 members 40 and 41 or of blocks 10 and 11 and the block 46, is a helical spring 50 whereby said block is urged away from said sides 40 and 41 or insulatory blocks 10 and 11 at all times.

55 By rotation of the screws 49, the block 46 may be drawn towards or forced away from the side member, and thus the condenser plate (1 or 2) mounted thereupon is advanced towards the movable condenser element or drawn away therefrom. The angular relation of plates 1 and 2 to plate 3 also may be regulated by the adjustment of screws 49 until such relation as is required is secured.

65 Referring now to Figure 7, it will be seen

that there are at the top of the frame adjusting screws 12 and 13 which engage a damping material 8 and 9, or any other suitable material may be employed, which material in turn is in contact with the tip of 70 said movable plate 3. This provides the major portion of the damping impedance. Additional damping impedances are obtained from the compression forces resulting from the movable plate 3 acting upon the 75 relatively thin sheet of air dielectric which exists between the fixed and movable plates 1, 2, and 3.

The improvement particularly obtained by 80 this damping arrangement in the present invention is that the damping impedances are symmetrically spaced and are equal to each other upon opposite sides of the movable plate.

In Figure 6, means are illustrated for absorbing the motion of the vibratory parts 85 of the reproducer and by which means this motion is largely absorbed and prevented from being transferred to the frame of the reproducer. By such absorption, troublesome reflection effects are eliminated, resulting in improved reproducing qualities of 90 tone reproduction.

Bushings 18 and 19 which surround the 95 fulcrum 4 absorb such motion and these bushings also center the vibratory parts in their normal position. Bushings 18 and 19 are seated in a body member 20 which is adjustably mounted upon the frame, thereby 100 providing means for producing the requisite tension upon the fulcrum. Set screw 21 and screw 22 passing through body 20 and bottom member 43 maintain body 20 in a fixed position upon said frame and said set screws 21 and 22 maintain the body 20 in position 105 after once adjusted relatively to the frame.

Referring again to Figure 4, which should 110 be read in conjunction with Figure 7, it is to be again noted that the plates 1 and 2 are mounted upon electrical insulating blocks 46. Means have already been described 115 whereby said blocks 46 with their attached metallic plates 1 and 2 may be adjusted to any position and spacing relative to the movable plate 3 by the use of adjusting screws 49 in conjunction with the compression springs 50.

Figure 8 discloses how the three adjusting 120 screws 49 are spaced in the corners of a triangle when viewed from the side of the reproducer. By virtue of the triangular arrangement of the adjusting screws 49, the insulating blocks 46 together with their metallic plates 1 and 2, may be tilted to any desired position relative to the movable plate 3 in addition to being moved toward and away therefrom. This tilting adjustment 125 provides means for obtaining a large variation in the percentage change in the capacitance relative to motion, thereby pro- 130

ducing quality variations in the sound output.

In each of the drawings, the screw for holding the needle is indicated by the numeral 50. The stylus or needle 5 is connected to the movable condenser plate 3 in the usual manner for ready replacement.

The present invention is designed to operate in conjunction with a modification of the vacuum tube amplifying system which is disclosed in applicant's co-pending application, Serial No. 309,551, filed October 1, 1928, and wherein a small change in the electrostatic capacity of a condenser of the type embodied in the present invention is used to cause a shift in the frequency of a radio-frequency oscillator. Such shift in frequency at either a constant or at a variable rate causes a large variation in the anode current of the associated vacuum tube, the current changing at a predetermined rate relative to the shift in the frequency of the radio-frequency oscillator.

Figure 9 illustrates such a modified type of circuit adapted to be employed for phonographic record reproduction with the condenser pickup illustrated in the preceding figures. In said Figure 9, the condenser element herein described and illustrated is indicated by three plates crossed by an arrow.

In Figure 9, fixed condenser plates 1 and 2 are disposed at opposite side of said movable condenser plate and are differentially connected to the electrical circuit there shown.

One of the fixed plates of the reproducer is connected to a circuit in which is disposed a fixed condenser C, such circuit terminating intermediate a choke-coil and the modulating circuit electrically connected to the plate of a vacuum tube.

The other fixed plate of the reproducer is electrically connected to the grid circuit of said vacuum tube. Said grid circuit is biased by a battery, and is electrically connected through the filament circuit to the movable condenser plate, there being inductance L' in said grid circuit, the coil extending across from the movable plate to the fixed plate last mentioned.

The plate circuit of such reproducing circuit is a tuned plate modulating circuit having in one side thereof inductance L'' and in the other side thereof, a capacity VC.

Disposed in the circuit is a choke-coil marked "Choke" and a plate circuit battery. A variation in the frequency of the oscillator coincident with movements of the movable condenser element 3 relative to the fixed condenser elements 1 and 2 produces augmented variation in the plate current, and these variations in the plate current affect the audiofrequency transformer T therein and, of course, the output of the circuit.

The movable condenser plate 3 is preferably of a type adapted to be flexed by move-

ment of the stylus 5, rather than one which will move upon a pivot or about a trunnion only. Such plate may be so arranged and constructed that the whole of the plate is moved or flexed, or it may be so designed that a portion only thereof is flexed as incident to movement of the stylus 5.

This particular feature of the invention is not limited in its utilities to an electrostatic reproducer but, on the other hand, may be employed with success with a magnetic reproducer.

Likewise, such structure may be made a part of a single plate vibratory condenser, or a condenser having one fixed plate and one flexible plate, or a device having a plurality of flexible plates in conjunction with a fixed plate, or a plurality of fixed plates in conjunction with a single flexible plate, or a plurality of flexible plates in cooperation with a plurality of fixed plates. The advantages by employing a plate which will flex, rather than one which is moved by the stylus, is that the adjustment of such a flexible plate is maintained over a greater period of time, and there is greater truthfulness in reproduction, it being possible to control to a finer degree the flexing movement of such a plate guided by a stylus. Of course, the movements of the plate are minute, and are rapid, so that much is gained by providing a mounting requiring the material of the plate to be flexed rather than to move about a point or pivot.

I claim:

1. An electrostatic reproducer for the reproduction of records comprising a flexible metallic plate associated with fixed metallic plates to form several variable capacity elements, said flexible plate being mounted at its ends beyond said fixed plates, the body of said flexible plate being between said fixed metallic plates in such a manner that inverse capacitance variations are produced simultaneously between said movable plate and said fixed plates by lateral movement of one of the extending ends of said flexible plate.

2. A condenser having a movable metallic plate associated with a fixed metallic plate to provide variable capacitance and in which said movable plate is flexed, and comprising a fixed plate having a plurality of supports each adjustable to advance or retract a part of said fixed plate relatively to said movable plate, and damping means movable toward and away from said movable plate.

3. A reproducer comprising a plurality of capacity elements having capacitances variable inversely, simultaneously, and relatively to each other, having a movable metallic element associated with a fixed metallic element to provide variable capacitance, and in which said movable element is flexed, and wherein there is a fixed plate having a plurality of supports each adjustable to advance or re-

tract a part of said fixed plate relatively to said movable element, and damping means movable toward and away from said movable element.

5 4. A reproducer of the electrostatic type for the reproduction of records comprising a movable member adapted to be flexed, one end thereof being disposed between damping means and the other seated in a housing, a 10 plate at each side thereof, a housing for said plates and member, means in said housing for advancing or retracting said plates relatively to said movable member, and damping means adjustably disposed relatively to said 15 movable member and in said housing.
